(57) CLAIM

The ornamental design for a pouch for attaching to an undergarment, as shown and described.

DESCRIPTION

FIG. 1 illustrates a front view of a pouch for attaching to an undergarment, where the pouch is in a closed configuration and an adjustable strap for the pouch is in an open configuration;

FIG. 2 illustrates the front view of the pouch for attaching to an undergarment, where the pouch is in an open configuration and the adjustable strap for the pouch is in an open configuration;

FIG. 3 illustrates a rear view of the pouch for attaching to an undergarment, where the pouch is in a closed configuration and the adjustable strap for the pouch is in an open configuration;

FIG. 4 illustrates a rear view of the pouch for attaching to an undergarment, where the pouch is in a closed configuration and the adjustable strap for the pouch is in a closed configuration;

FIG. 5 illustrates a first side view of the pouch for attaching to an undergarment, where the pouch is in a closed configuration and the adjustable strap for the pouch is in a closed configuration;

FIG. 6 illustrates a second side view of the pouch for attaching to an undergarment, where the pouch is in a closed configuration and the adjustable strap for the pouch is in a closed configuration;

FIG. 7 illustrates a top view of the pouch for attaching to an undergarment;

FIG. 8 illustrates a bottom view of the pouch for attaching to an undergarment;

FIG. 9 illustrates a perspective view of the pouch for attaching to an undergarment, where the pouch is in an open configuration and the adjustable strap for the pouch is in an open configuration;

FIG. 10 illustrates a perspective view of the pouch for attaching to an undergarment, where the pouch is in an open configuration, the adjustable strap for the pouch is in a closed configuration, and the pouch is attached, by the adjustable strap, to an undergarment worn by a person; and,

FIG. 11 illustrates a perspective view of the pouch for attaching to an undergarment, where the pouch is in a closed configuration, the adjustable strap for the pouch is in a closed configuration, and the pouch is attached, by the adjustable strap, to an undergarment worn by a person. The broken lines in FIGS. 1-11 illustrate fastening elements and stitching representing portions of the article that form no part of the claimed design. The broken lines in FIGS. 10-11 illustrate a person and an undergarment and represents environment that forms no part of the claimed design.
